United States Patent Office.

JOSHUA REGESTER, OF BALTIMORE, MARYLAND.

Letters Patent No. 92,470, dated July 13, 1869.

IMPROVED ROTATING BELL AND BELL-WHEEL.

The Schedule referred to in these Letters Patent and making part of the same.

To all whom it may concern:

Be it known that I, JOSHUA REGESTER, of the city and county of Baltimore, in the State of Maryland, have invented a new and improved Mode of Hanging Large Bells, and of Constructing the Wheels therefor; and I do hereby declare that the following is a full, clear, and exact description thereof, reference being had to the accompanying drawings, making part of this specification, in which—

Figure 1 is a top view of a bell hung by its oscillating yoke, and having my improvements applied to it.

Figure 2 is a diametrical section through the improved bell and bell-wheel, applied to the bell-yoke, which latter is shown partly in section.

Figure 3 is a view of two segments of the improved wheel.

Similar letters of reference indicate corresponding parts in the several figures.

The nature of my invention consists, first, in keys or pins for both sustaining the bell independently of the bolt which sustains the clapper, and for permitting of the desired adjustment of the bell, said pins being so applied, that when tightened, they hold the bell from turning around the clapper, but when loosened, will permit it to be turned so as to present new striking-surfaces to the clapper. I am aware of contrivances for turning a bell continuously during the striking-operation. I also am aware of bells having been suspended upon a square bolt, such bolt carrying the clapper and the bell, both being suspended by a bolt, which is held in position by a removable key-cap. My mode of employing keys for sustaining the bell independently of the clapper-support, and for permitting the bell to be periodically turned a short distance around the clapper without unshipping the bell, is an improvement over the modes referred to, and previously invented.

My invention consists, second, in the combination of a metal hub, with hollow spoke-sockets, a series of wooden spokes, and a series of metal overlapping felloes, of a form adapted for forming a ring with a groove in its periphery, the said parts being all united together by screws or bolts, all as hereinafter explained, and as represented in the drawings.

This combination of parts enables me to make a strong, light, and durable bell-wheel.

I am aware that wagon and other wheels have been made of wood and metal combined, but I am not aware that a pulley, or any other grooved wheel, has been formed as I have shown and described.

If a wheel is made out of wood entire, it must be made very heavy, in order to be strong enough; and if made entirely of metal, it will be too expensive, and too heavy.

To enable others skilled in the art to understand my invention, I will describe its construction and operation.

In the accompanying drawings—

A is the bell;

B, the oscillating yoke, with trunnions b b on its extremities; and

C, the bell-wheel or pulley, over which the bell-rope passes.

The tapering hub or ear a, at the crown of the bell, has an annular groove, d, formed in its perimeter, near its upper end, which groove coincides or matches with a corresponding groove, d, formed in the yoke B, as shown in fig. 2.

When the bell is applied to the yoke, and two keys c c are driven through the yoke, so as to pass through the grooves d d, the attachment of the bell to its yoke will be effected, and the bell may be turned about its axis by simply loosening said keys, without disconnecting or unhooking the bell from its yoke.

The keys c c are arranged on opposite sides of the ear or hub a, and pass transversely through the yoke; and these keys may be locked in their places by pins passed through their smallest ends, as shown in fig. 1.

The clapper D' is pivoted to a hanger, h, by a pin, j, passing through eye k, which hanger receives, through a square hole made centrally through its head, a square-shanked bolt, f, having a head, i, formed on its lower end.

This square-shanked bolt passes loosely through a hole made through the bell, and centrally through the hub or ear a, as shown in fig. 2, and receives upon it a key-cap, e, and a nut, g.

The hanger h cannot turn about the bolt f, nor can the cap e turn about this bolt, as they both fit snugly upon the prismatic portion of this bolt; and the cap e has lugs o o formed on its lower side, which, when this cap is in place on the yoke, will enter recesses made in the yoke.

By this arrangement and construction of parts, it will be seen, that by loosening the nut g and the two keys c c, the bell can be adjusted about its axis without having the clapper to turn about its axis, or detaching the bell from its yoke.

After adjusting the bell, the keys c c and nut g are set up tight again.

The wheel C consists of a metal rim, wooden spokes, and a metal hub.

The hub H is constructed with radial tubular sockets, t, around it, for receiving the spokes S; and the rim is made up of metal segments, or half-felloes, G G, secured together so as to overlap one another at the ends, and thus break joints.

These segments are made so as to form sockets, s', when secured together, for receiving the tenons, s, on the outer ends of the spokes S, as shown in figs. 2 and 3; and the segments are also made so as to leave an annular groove around the wheel when they are secured together by screws or rivets p.

A bell-wheel can be constructed in this way so that it will be very light, and still possess great strength.

The hub or ear a is made slightly tapering, and fitted

into a corresponding socket in the yoke, so that when the keys *c c* are driven hard into their places, they will draw the said hub or ear tightly into its socket; and when these keys are loosened, the bell will settle sufficiently to loosen it, and allow it to be turned about its vertical axis.

Having described my invention,

What I claim as new, and desire to secure by Letters Patent, is—

1. Fastening the bell to its yoke by means of the keys *c c*, substantially as described, and for the purpose set forth.

2. The groove in the hub of the bell, in combination with the groove in the yoke, and with the keys *c c*, substantially as described.

3. The combination of the metal hub, having sockets, the wooden spokes, and the overlapping socketed flanged felloes, the same constituting an improved bell-wheel, as set forth.

JOSHUA REGESTER.
